US0D1029075S

(12) **United States Design Patent** (10) Patent No.: **US D1,029,075 S**
(45) Date of Patent: ** May 28, 2024

(54) **CAMERA LENS**

(71) Applicant: **SHENZHEN NEEWER TECHNOLOGY CO.LTD**, Shenzhen (CN)

(72) Inventors: **Jun Wang**, Shenzhen (CN); **Yan Ke**, Shenzhen (CN)

(**) Term: **15 Years**

(21) Appl. No.: **29/891,756**

(22) Filed: **May 9, 2023**

(51) LOC (14) Cl. **16-01**

(52) U.S. Cl.

USPC **D16/219**

(58) **Field of Classification Search**

USPC D16/206, 211, 217, 218-219, 220; D10/46, 104.1, 114.6; D14/195, 228, 506

(57) **CLAIM**

The ornamental design for a camera lens, as shown and described.

DESCRIPTION

FIG. 1 is a front, right and top perspective view of a camera lens showing our new design;
FIG. 2 is a rear, left and bottom perspective view thereof;
FIG. 3 is a left view thereof;
FIG. 4 is a right view thereof;
FIG. 5 is a top view thereof;
FIG. 6 is a bottom view thereof;
FIG. 7 is a front view thereof; and,
FIG. 8 is a rear view thereof.
The broken lines in the drawings illustrate portions of the camera lens that form no part of the claimed design.

1 Claim, 8 Drawing Sheets
